DESIGN FOR A REFRIGERATED DISPENSING CABINET

George W. Cocks, Upper Montclair, N. J.

Application October 6, 1937, Serial No. 72,031

Term of patent 7 years

To all whom it may concern:

Be it known that I, George W. Cocks, a citizen of the United States, residing in Upper Montclair, county of Essex, and State of New Jersey, have invented a new, original, and ornamental Design for a Refrigerated Dispensing Cabinet, of which the following is a specification, reference being had to the accompanying drawing, forming a part thereof, in which:

Fig. 1 is a front perspective view of a refrigerated dispensing cabinet showing my new design; and

Fig. 2 is a rear perspective view thereof taken from a point opposite the view shown in Fig. 1.

I claim:

The ornamental design for a refrigerated dispensing cabinet, substantially as shown.

GEORGE W. COCKS.
